UNITED STATES PATENT OFFICE.

LOUIS PELOQUIN, OF SOUTHERBRIDGE, MASSACHUSETTS.

WINDING-DRUM.

1,157,897.

Specification of Letters Patent. Patented Oct. 26, 1915.

Application filed February 24, 1914. Serial No. 820,528.

To all whom it may concern:

Be it known that I, LOUIS PELOQUIN, a citizen of the United States, residing at Southbridge, in the county of Worcester 5 and State of Massachusetts, have invented a new and useful Winding-Drum, of which the following is a specification.

This invention relates to a winding drum and connected parts, chiefly for use with a 10 billiard chalk holder.

The principal objects of the invention are to provide an improved form of bracket for holding the drum and especially a simplification of the ordinary bracket used for 15 that purpose; to provide rolls connected with said bracket in such way that the friction of the cord will be very materially reduced, and especially to provide improvements in the drum itself for the purpose of 20 simplifying and cheapening the construction and permitting of the convenient and expeditious taking out and putting in of the central shaft and spring so that the latter may be repaired or adjusted. The invention 25 also involves improvements in details of construction of the said drum and its connected parts.

Reference is to be had to the accompanying drawings in which,

30 Figure 1 is an end view of a billiard chalk holder and winding drum constructed in accordance with this invention; Fig. 2 is a front elevation of the same; Fig. 3 is a central sectional longitudinal view of the drum 35 and the interior parts; and Fig. 4 is a plan of the blank for the drum extended out in a plane.

The invention is shown as involving a supporting bracket A, and a winding drum 40 B for receiving a cord C for a chalk holder D. The bracket A comprises a plate 10 adapted to be secured to the ceiling or to the bottom of a billiard table and provided with two downwardly slanting legs 11 to 45 which the drum is journaled, as will appear hereinafter. These parts are made of a single piece of sheet metal and what I called a plate 10 consists of two of said pieces of metal bent around and brought 50 into a plane. Between these two portions is formed a guide tongue 12 consisting of two straps of the metal bent down into parallelism with each other and integrally connected at the bottom. They are in plane 55 parallel with the planes of the legs 11.

This tongue is made on a curve corresponding with the curve of the drum B, as will appear, and is provided with two antifriction rolls 13 which engage the cord C no matter whether it is pulled up or down.

The drum itself is made of a single sheet of metal, as indicated in Fig. 4. This sheet is composed of four parts. Two substantially rectangular parts, 14 and 15, and two substantially circular parts 16 and 17 constituting ends. The rectangular part 14 is provided with a slit at one end to form a tongue 18 which, when the parts are assembled, extends into a slot 19 in the circular end piece 17. At the inner end the 70 part 14, and at both ends the part 15, is provided with a semi-circular slit 20. These slits form ears 21 on the end pieces and these end pieces are also provided with additional ears 21 of the same shape. The 75 rectangular part 15 is also provided with a key slot 22. The end piece 16 is provided with a slit to form a tongue 23 at a short distance from the center and both end pieces have circular perforations 24 and 25, respectively, at their centers. In addition to this, the end piece 17 has a preferably circular perforation 26 considerably larger than the perforation 25. This part having been stamped out of sheet metal, it is bent 80 up preferably by dies so as to form a substantially cylindrical drum, as indicated in the other figures. When this is done the two parts 16 and 17 constitute the circular 85 ends of the cylinder while the two parts 14 and 15 constitute two spaced sections of a cylindrical surface between said ends. The 90 ears 21, four of which are shown on each end piece, stick out beyond the cylindrical portion of the drum to guide the cord.

The drum is provided with a central shaft 30 having a small end 31 separated from the main portion of the shaft by a shoulder 32 near the end. This end 31 just fits the circular perforation 25 in one end of the drum. The perforation 24 in the other end of the drum is just enough larger to receive the opposite end of the shaft and constitute a bearing therefor. Fixed to one end of the shaft is a spring 33 having an opposite free 100 end 34. The perforation 26 is large enough to permit the insertion of the shaft with the spring thereon.

The cord C is provided with a knot at the end which is slipped through the key hole 110

slot 22, as is well understood in this art. This cord passes through the tongue 12 between the rollers 13.

Assuming the roller to be formed up into 5 shape, it is attached to the legs 11 of the bracket by means of screws 36 which extend into the ends of the shaft and hold the shaft in stationary position. When it is 10 desired to remove the shaft to repair or adjust the spring, or for any other purpose, these screws are taken out and the drum removed from the bracket, then the shaft is pulled by the projecting end which extends through the perforation 24 until the opposite 15 end of the shaft is within the drum and then this is moved sidewise so as to make it extend out through the perforation 26. This end is then grasped and the shaft and the attached spring can be removed. 20 In re-assembling these parts the large end of the shaft 30 and the free end of the spring 34 are introduced into the opening 26 and the parts manipulated by the other end of the shaft until the farther end of 25 the shaft is caused to extend through the perforation 24, then the shaft is further manipulated to get the opposite end entirely within the drum and have it project out through the perforation 25. The object of 30 the inwardly projecting tongue 23 will now be seen. This serves as a ratchet tooth for the end 34 of the spring. If the drum is rotated in the wrong direction, this tooth easily passes over the free end of the spring 35 once during each revolution. When turned in the direction to wind up the spring, this end necessarily catches under this tongue and holds that end of the spring so that, the shaft being held stationary and the 40 drum turned, the spring will be wound up and will cause the cord to wind up automatically on it whenever released after being pulled out. It will be seen, therefore, that the drum is supported and the cord 45 guided by a very small sheet metal bracket and the cord is prevented from having undue friction by the rolls no matter which way the cord is pulled out. Moreover, the drum is formed of a single sheet of metal 50 and the spring and shaft are easily assembled therein and brought into operative condition without any nice adjustments of any kind.

Although I have illustrated and described 55 only a single embodiment of the invention, I am aware of the fact that many modifications can be made therein by any person skilled in the art without departing from the scope of the invention as expressed in the claims. Therefore, I do not wish to be limited to all the details of construction shown and described, but—

What I do claim is:—

1. In a chalk holding drum, the combination of a shaft, means for holding said

shaft in fixed position, a drum for receiving said shaft, said drum having a central perforation in each end fitting the ends of the shaft, a spring fixed to the shaft near one end and having a free end, the other end of said drum having means for engaging and holding the free end of the spring when the drum is rotated in one direction, and releasing it when rotated in the other direction, said means consisting of an inwardly 75 extending tongue on the end of the drum.

2. In a chalk holding drum, the combination of a shaft, means for holding said shaft in fixed position, a drum for receiving said shaft, said drum having a central perforation in each end fitting the ends of the shaft, one end of the shaft having a reduced end provided with a shoulder, whereby said shaft can be disconnected from the drum by drawing its reduced end inwardly from the 80 bearing of that end of the drum, a spring fixed to the shaft near said reduced end and having a free end, the other end of said drum having means for engaging and holding the free end of the spring. 85

3. In a chalk holding drum, the combination of a shaft, means for holding said shaft in fixed position, a drum for receiving said shaft, said drum having a central perforation in each end fitting the ends of the shaft, 95 one end of the shaft having a reduced end provided with a shoulder, a spring fixed to the shaft near said reduced end and having a free end, the other end of said drum having means for engaging and detachably holding the free end of the spring, whereby said shaft can be disconnected from the drum by drawing its reduced end inwardly from the bearing on the drum, and said drum having a perforation through which 100 the shaft and spring can be withdrawn. 105

4. The combination with a chalk holding drum, of a shaft on which it is rotated, said drum having a perforation for each end of the shaft, one perforation being smaller than 110 the other and one end of the shaft being smaller than the other, a spring on the shaft connected with the drum, said drum having a second perforation through one end thereof, through which the shaft and spring can 115 be withdrawn and replaced.

5. The combination with a chalk holding drum, of a shaft on which it is rotated, said drum having a perforation for each end of the shaft, a spring on the shaft having one 120 end connected with the drum by a ratchet, said drum having a second perforation through one end thereof, through which the shaft and spring can be withdrawn and replaced.

6. As an article of manufacture, a winding drum comprising two rectangular main parts and two circular end parts connected together, each end part having a plurality of ears projecting beyond the circumference 125 130

thereof and also having a central perforation constituting a bearing, one of the main parts having an integral tongue and one end a slot for receiving it whereby the said parts are fixed together at one edge, a shaft journaled in said perforations, and a spring for connecting the shaft with the drum.

In testimony whereof I have hereunto set my hand, in the presence of two subscribing witnesses.

LOUIS PELOQUIN.
